UNITED STATES PATENT OFFICE.

LOUIS A. CORNELIUS, OF GRAND RAPIDS, MICHIGAN.

PLUMBING WASTE-PIPE.

1,096,225.

Specification of Letters Patent.

Patented May 12, 1914.

Application filed April 19, 1913. Serial No. 762,305.

To all whom it may concern:

Be it known that I, LOUIS A. CORNELIUS, a citizen of the United States, residing at Grand Rapids, in the county of Kent and 5 State of Michigan, have invented new and useful Improvements in Plumbing Waste-Pipes, of which the following is a specification.

My present invention relates to plumbing 10 waste-pipes, and its object is to provide such a pipe and controlling cock which may be easily applied to wash-basins, etc., of different dimensions; and further, which shall have an improved controlling cock; and further, which shall be improved in various 15 particulars hereinafter appearing; and further, which shall be in simple, and effective manner combined with the overflow-pipe of the basin, etc. These objects are attained by, 20 and my present invention finds a preferable embodiment in, the structure hereinafter described and illustrated by the accompanying drawings, in which:—

Figure 1 is a vertical central sectional view of the whole device: Fig. 2 is a front view of the same, certain parts being shown in vertical central section on a plane at right angles to that on which Fig. 1 is taken: Fig. 3 is a top plan view of 25 the same: Fig. 4 is a fragmentary view of parts on the same sectionizing plane as Fig. 1: Fig. 5 is a horizontal section of the structure on a plane corresponding with line A—B of Fig. 1: Fig. 6 is a like view of the 30 same, on a plane corresponding with line C—D of Fig. 1; and Fig. 7 is a side view of the cock's movable valve member.

The position of a wash-basin 1 to which my device is shown as applied, is indicated 40 in dotted lines in Fig. 1,—the top portion at 2, and the bottom of the basin at 3. Both the waste and the overflow from the basin pass through a common outlet 5, intermediate pipe 4 and ultimate discharge pipe 6.

When the waste-pipe function of the device 45 is closed by the cock 7, (in the position of the parts shown in Fig. 1,) the overflow-pipe function of the device is operative, the overflow water passing from the pipe 4, 50 through the by-pass or laterally-enlarged portion 8 of the vertical pipe 9, outside the cock-controlling lower pipe 10, over its top and down through it and through the hollow movable valve member 11, and is thence discharged through the ultimate pipe 6: When 55 however the cock is opened, the waste water

escapes directly from the pipe 4, through the cock's stationary valve member or valve seat 12, into such pipe 6.

The movable valve member has a helical movement in opening and closing, being guided therein as by the fixed lug 13 engaging said member's helical groove 14: This movement is imparted through a spline-like engagement of the cock-controlling upper 60 pipe 16 (carrying the rotary handle 15) with the lower pipe 10, which is concentric with and surrounded by said upper pipe, these two pipes being sufficiently separated as shown to permit the free passage of overflow water therebetween. The said spline-like engagement comprises the radially extending lugs 17 on the lower pipe 10 engaging the longitudinal slots 18 in the upper pipe 16. It will be seen that such spline-like 65 engagement permits the helical movement of the valve member 11, and also affords an adjustability of the device to basins, etc., whose upper portions 2 and bottoms 3 are at different distances apart; for the bearing 70 member 19 in which rotates the upper pipe 16 may be secured to the upper portion 2 as by its threaded downwardly-extending tube portion 20 with its nut 21 adapted to be screwed to its engagement with the under 75 side of the upper portion 2 of the basin, while the lower parts—lower pipe 10, valve member 11, etc.,—are supported otherwise, as by the pipes 6, 4, etc. It will also be seen that the inner walls of the vertical pipe 9 80 extending, as they do, for more than an arc of 180 degrees around the valve member 11, afford it a sufficient bearing for its helical movement, although the remaining portion of this member's circumference opens on the 85 by-pass 8. It will also be seen that by reason of the lug 13 being screw-threaded as shown, it may be unscrewed to permit the 90 ready disassembling of the parts.

Not confining myself to details of construction shown or described, I claim:—

1. In a device of the character described, a basin, a combined waste-pipe and overflow-pipe leading from the basin's outlet below its overflow level and having a valve seat, a 105 helically movable hollow valve co-operating with the valve seat and contained within and spaced from the pipe and extending above the basin's outlet, a removable lug to guide the valve's movement, and a rotatable handle 110 for operating the valve in splined relation thereto.

2. In a device of the character described, a basin, a combined waste-pipe and overflow-pipe leading from the basin's outlet below its overflow level and having a valve seat, and a hollow helically-movable valve coöperating with the valve seat and contained within and spaced apart from the pipe and extending above the basin's outlet, and a handle to operate the valve.
- 10 3. In a device of the character described, a basin, a combined waste-pipe and overflow pipe leading from the basin's outlet below its overflow level and having a valve seat, and a hollow helically-movable valve coöperating with the valve seat and contained within and spaced apart from the pipe and extending above the basin's outlet, the pipe having on one side a lateral enlargement to permit the free passage of overflow water along a portion of the valve.
- 15 4. In a device of the character described, a basin, a combined waste-pipe and overflow-pipe leading from the basin's outlet below its overflow level and having a valve seat, and a hollow valve coöperating with the valve seat and contained within and spaced from the pipe and extending above the basin's outlet, and a rotatable handle for operating the valve and having a downwardly-extending pipe with longitudinal slots and surrounding and spaced from the valve, the

- valve having lugs in spline-like engagement with the slots.
5. In a device of the character described, a basin, a combined waste-pipe and overflow-pipe leading from the basin's outlet below its overflow level and having a valve seat, and a hollow helically-movable valve coöperating with the valve seat and contained within and spaced apart from the pipe and extending above the basin's outlet, and a rotatable handle for operating the valve in splined relation thereto.
6. In a device of the character described, a basin, a combined waste-pipe and overflow-pipe leading from the basin's outlet below its overflow level and having a valve seat, a hollow valve coöperating with the valve seat and contained within and spaced from the pipe and extending above the basin's outlet, a rotatable handle for operating the valve in splined relation thereto, and a bearing member for the handle and having a threaded portion and a nut thereon for fastening said member stationarily.

In testimony whereof I have hereunto set my hand in presence of subscribing witnesses.

LOUIS A. CORNELIUS.
